Benjamin Sandor

By Albert E. Lynch.

Attorney

UNITED STATES PATENT OFFICE.

BENJAMIN SANDOR, OF CLEVELAND, OHIO.

HEEL.

Application filed November 19, 1923. Serial No. 675,466.

To all whom it may concern:

Be it known that I, BENJAMIN SANDOR, a citizen of the United States, residing at Cleveland, in the county of Cuyahoga and 5 State of Ohio, have invented certain new and useful Improvements in Heels, of which the following is a specification.

This invention relates to improvements in heels for shoes and more particularly to 10 means for providing a detachable connection between the upper and lower lifts of a heel when the lower lift is what is commonly termed a rubber heel.

One of the objects of my invention is the 15 provision of cooperating means on the upper and lower lifts for enabling the lower lift to be readily and effectively attached to the upper lift without necessitating the use of unsightly securing means.

20 A further object of my invention is the provision of means for detachably connecting the upper and lower lifts of such a character that the wearer himself can interchange the lower lifts to correct uneven 25 wear and thereby effect economy in the use of the heels.

My invention also contemplates the provision of a connecting device the employment of which will give added resiliency to 30 the complete heel.

I carry out the above objects by providing two interlocking members, one of which is adapted to be rigidly attached to an upper lift and the other of which is adapted to 35 be rigidly secured to the lower lift. The member attached to the lower lift is adapted to fit snugly within the member attached to the upper lift to prevent relative movement between the lifts during use. A single securing member extends between the lifts and serves to lock the co-operating members 40 together. This securing member is arranged to be inserted from the forward face of the lift and is therefore ordinarily concealed from view.

The means for carrying out my invention will be hereinafter more fully set forth in the following description, which pertains to the accompanying drawings. The essential 50 features of my invention will be summarized in the claims.

In the drawings Fig. 1 is a side elevation of a shoe, showing a longitudinal section through a heel embodying my invention; 55 Fig. 2 is a bottom view, showing the lower lift removed. Fig. 3 is a section taken on

line 3—3, Fig. 2; Fig. 4 is a plan view of the lower lift and one of the inter-locking members attached thereto. Fig. 5 is a section on line 5—5, Fig. 4.

60

My invention broadly comprises a pair of co-operating members, one of which is permanently attached to the upper lift of a heel and the other of which is permanently attached to the lower lift. Accordingly, in 65 the various figures, I have shown an upper lift at 10 and a lower lift at 11.

The upper inter-locking member, as shown in Figs. 2 and 3, comprises preferably an 70 endless plate 12, which is shaped to the outline of a heel and is arranged to be attached by securing means 13, to the upper lift. This securing member may be either a stamping or a casting of light material. The plate may be chamfered, as at 14, to 75 provide a space within which the interlocking member on the lower lift may extend, whereby the over-all depth necessary to effect the interlocking may be reduced to a minimum. A tongue 15, having a threaded 80 opening 16 therein, is shown on an arm 17, which is disposed intermediate the member 12 and the upper lift, and is shown as positioned therein by securing members 18. The plate 12 may be provided with a passageway 19 and a recess 20 to receive a locking 85 device which serves to secure the interlocking members together.

The lower interlocking member is illustrated in Figs. 4 and 5 as a plate 25, which is spaced from the lower lift preferably by 90 strips of leather 26, to provide a passageway 29. To secure the plate 25 to the lower lift, I have shown attaching screws 28, which extend through openings in the strips 95 26 and also through the plate 25, and are adapted to be anchored in facing pieces 27, which as shown in Fig. 5, are disposed on the upper side of the plate. The plate 25 is shown as having a slot 30 adjacent the rearward end of the passageway 29, which slot is arranged to receive the tongue 15, when the lower member is brought to the proper position for interlocking with the upper member.

100 To lock the upper and lower co-operating members, I may provide a screw 31 which extends through the passageway 19 on the upper lift, and then through the passageway 29 on the lower lift, and is threaded 110 to engage the threaded opening 16 in the tongue. The relative position of the co-

operating members when in locked position is shown in Fig. 2.

In view of the foregoing description, it will be understood that I have provided a simple and effective means for locking together the upper and lower lifts of a heel.

An advantage of my invention is that the lifts may be readily interchanged by the operation of only a single securing member which is ordinarily concealed by the sole-piece of the shoe. A further advantage of my invention is the reduction of the overall depth of the heel which is occasioned by the nesting of the interlocking members.

Having thus described my invention, I claim:

1. A device for connecting the lifts of a heel, comprising in combination, a member rigidly attached to the upper lift and comprising a hollowed-out plate and an arm carried by said plate and extending rearwardly and centrally of the hollowed out portion of said plate, a second member having the periphery thereof shaped to enter the opening within the first mentioned plate, and having a transversely extending slot adapted to receive a portion of said arm, the second named member, having a longitudinally extending passageway terminating adjacent said slot, and the first named mem-

ber having a passageway leading from the forward face thereof in registration with the passageway in the second named member, and means extending through said passageways and engaging said arm for locking said members together.

2. A device for connecting the lifts of a heel comprising in combination, a plate having an outline conforming to the shape of a heel, and having an opening corresponding to the outline defined by the heel, an L-shaped member having a threaded opening in one arm thereof, and having the other arm rigidly connected to said member, a second member carried by the lower lift and having a passageway extending longitudinally and leading from the forward face, said second named member also having a slot extending transversely thereof and terminating adjacent the rearward end of the passageway therein, the arm having the threaded opening being adapted to extend through said slot, and a screw extending through said passageways and being in threaded engagement with said opening for locking said members together.

In testimony whereof I affix my signature.

BENJAMIN SANDOR.
